PISTON RING

Filed June 27, 1931

UNITED STATES PATENT OFFICE

CHARLES A. MARIEN, OF ST. LOUIS, MISSOURI, ASSIGNOR TO RAMSEY ACCESSORIES MANUFACTURING CORPORATION, OF ST. LOUIS, MISSOURI, A CORPORATION OF MISSOURI

PISTON RING

Application filed June 27, 1931. Serial No. 547,224.

My invention has relation to improvements in piston rings for internal combustion engines and it consists in the novel features of construction more fully set forth in 5 the specification and pointed out in the claim.

Briefly, the invention is directed to a one-piece ring known in the trade as a "snap ring" because of the inherent tension in the ring for holding it in intimate contact with the 10 cylinder wall. The amount of tension required to give satisfactory ring performance in automobile engines as formerly designed is no longer sufficient in the high speed engines of today. Ring manufacturers have 15 sought to keep step with the engine manufacturers by "loading" the rings with tension. That is, steadily increasing the ring tension to satisfy the increased demands on the ring, so that snap rings now have sufficient tension to bear against the cylinder wall with approximately twice the pressure 20 than formerly.

The efficiency of a piston ring in holding 25 compression and preventing oil leakage past the piston is dependent on the unit pressure with which the working face bears against the ring and the speed with which the ring responds to irregularities in the cylinder wall. Therefore, many ring manufacturers 30 have decreased the area of the ring working face by narrowing the ring and by providing channels in the ring face. A reduction in the cross-section of the ring in this manner 35 also increases its flexibility, which, together with an increase in the ring tension enables the ring to respond rapidly to cylinder wall variations and give efficient operation.

However, the reduction in the amount of 40 ring surface contacting with the cylinder wall naturally increases the amount of wear on this contacting surface and, although the ring will "wear in" quickly, its efficient life is greatly shortened. A contributing cause to the shortened life of a ring having its 45 working face thus reduced, is the fact that the ring does not bear against the cylinder wall with equal pressure throughout its entire circumference. A one-piece ring when 50 operating in a cylinder may have a bearing pressure of 10 lbs. across its diameter at right

angles to the diameter through the gap, and only 2 lbs. pressure across the gap diameter. This is so because the center of expansion of the ring is opposite to the gap, and the pressure of the surface of the ring at points 55 90° from the gap is exerted perpendicularly against the cylinder wall. Hence the entire ring tension is exerted against the cylinder wall at these points, while only a part of the ring tension is exerted at intermediate points. After the ring has become only slightly worn 60 adjacent to the gap, the ends of the ring will exert practically no pressure on the cylinder wall and the point diametrically opposite to the gap will exert very little pressure. Obviously, this unequal pressure at different 65 points in the circumference of the ring causes unequal wear on the working face of the ring—the points at right angles to the gap 70 wearing down most rapidly. Rings, having a circumferential groove, become so badly worn within 5000 miles of car operation that they must be replaced. Many have been removed from engines after 3000 miles of 75 service and clearly show excessive wear on opposite sides of the ring face 90° from the gap as illustrated in Fig. 6.

In order to reduce this rapid wear and resulting decrease in the life of the ring I have provided a ring with a greater amount of working surface at the points subjected to the greatest pressure so that the wear will be equalized around the entire circumference of the ring. In fact, the working surface 80 of the ring is substantially proportional in extent to the pressure of the ring against the cylinder wall throughout the circumference of the ring. This will be more readily apparent from the detailed description of the 85 ring which is to follow.

Another object of the invention is to provide on the face of the ring oil scraping edges that are inclined with respect to the cylinder wall instead of rectilinear as heretofore, so that these edges will exert a shearing 90 effect on the oil film on the cylinder wall. This will also appear more clearly from the detail description of the invention in connection with the accompanying drawing, in 95 which:

Figure 1 is a side elevation of my improved piston ring shown in place in a ring groove in a piston; Fig. 2 is a cross-section through the piston taken on the line 2—2 of Fig. 1, the piston ring being shown in edge view; Fig. 3 is a side elevation of the piston ring taken at right angles to the elevation shown in Fig. 1; Figs. 4 and 5 are enlarged cross-sectional details taken on the lines 4—4 and 10 5—5 of Fig. 2; and Fig. 6 is a diagrammatic view of an old style ring showing the uneven wear of the ring face due to nonuniform wall pressure.

Referring to the drawing, 1 represents my improved piston ring positioned in the groove *g* of piston *P* adapted to operate within an engine cylinder *C*. The ring 1 is split at *s*, the abutting ends 2, 2 of the ring (in the present instance) being cut to form a 15 step joint. However, any common type of joint, such as the plain butt, or bevel may be used. As heretofore pointed out, the ring is provided with inherent tension so it will 20 expand against the wall of the cylinder *C*; in order to adapt the ring for use in high speed engines, the amount of working surface is reduced by the provision of channels 25 4, 4', 4' in the ring face 3. As explained above, the reduction of the extent of working 30 surface enables the ring to "wear in" more quickly than otherwise, and the channels also reduce the cross-sectional area of the ring and increase its flexibility.

It will be observed that the channel 4 extends approximately over one-half the face 35 of the ring and is in the shape of an elongated rhomboid, the acute angles 5, 5 of which are rounded and are slightly less than 180° apart. The short diagonal across the obtuse angles 6, 6 of the rhomboid shaped channel 4 is diametrically opposite to the gap *s* of the ring. Thus, the sides 7, 7 of the channel are inclined with respect to the axis of travel *x* of the ring. At the same time, the 40 working face of the ring is greatly reduced in thickness directly opposite the gap *s* from which point it gradually widens till the working face is widest at the vertices of the angles 5, 5. Extending from each end 2 of the ring through an angle slightly less than 45 90° are the triangular channels 4', 4', the widest portion of the channels being of the same width as the widest portion of channel 4, and the channels 4', 4' being narrowest at the vertices of the acute angles 5' opposed to the angles 5. It will be observed that the channels 4 and 4', 4' are spaced a slight distance from each other so that the working 50 surface of the ring extends clear across the face of the ring along opposite lines 90° from the ring gap. Obviously, the channels 4', 4' may extend across the gap *s* instead of terminating just short of said gap. Thus, when the gap is closed the channels 4', 4' would 55 connect to form a continuous channel.

It has been shown above that the ring bears with the greatest pressure against the cylinder wall across its diameter perpendicular to the gap diameter so that the greatest amount of wear is on this part of the ring face. It is to compensate for this greater amount of wear that I have shaped the channels 4 and 4' as above described so as to provide greater amount of ring wearing surface at these points of greatest wear. The wear 70 on the working face of the ring gradually decreases around the circumference to the ring gap and directly opposite the ring gap, and the extent of working surface around the circumference of the ring decrease proportionately to this decrease in wear. 75

The edges of the walls 7, 7 of the channels serve to scrape excess oil from the surface of the cylinder wall during the travel of the ring over the wall and since these edges are inclined slightly with respect to the direction of travel of the ring, they will operate more efficiently owing to their shearing action than would a scraping edge that is perpendicular to the direction of travel. The oil that is removed from the cylinder wall by the action of these oil scraping edges accumulates in the channels 4, 4' from which it gradually drains back into the crankcase through the slots 8 traversing the ring 1 within the 80 channels 4, 4'. 85

Having described my invention, I claim:

A split piston ring having a plurality of channels in its face, said channels being wedge-shaped and widest adjacent to the ring gap and diametrically opposite thereto, and said channels being narrowest at points substantially 90° from the ring gap. 100

In testimony whereof I hereunto affix my signature. 105
